J. HEARD

SCREEN DOOR CLIP

Filed Sept. 25, 1922

Patented July 24, 1923.

1,463,119

UNITED STATES PATENT OFFICE.

JOHN HEARD, OF STRATHROY, ONTARIO, CANADA.

SCREEN-DOOR CLIP.

Application filed September 25, 1922. Serial No. 590,282.

To all whom it may concern:

Be it known that I, JOHN HEARD, of the town of Strathroy, in the county of Middlesex, Province of Ontario, Canada, a subject 5 of the King of Great Britain, have invented certain new and useful Improvements in Screen-Door Clips, of which the following is a specification.

This invention has relation to certain new 10 and useful improvements in a screen door clip and has for its primary object the provision of a device of this character which may be readily mounted on the door and door frame for interlocking engagement 15 when the door is closed.

The invention has for another object the provision of a screen door clip of the character stated which will be composed of a receiving member for removable mounting 20 on the door frame and an engaging member removably carried by the door, these parts being detachably mounted on their respective supports in such a manner that they will automatically interlock as the door is closed.

25 A further object of the invention resides in the provision of a screen door clip of the character stated in which the parts will be of simple construction and may be readily manufactured at small cost and applied to 30 the door and door frame without injury thereto.

With the foregoing and other objects in view as will appear as the description proceeds, the invention consists in the novel 35 construction, combination and arrangement of co-operating elements as hereinafter more specifically set forth, claimed and shown in the accompanying drawings forming a part of the present application, in which:

40 Fig. 1 is an elevation of a portion of a door and door frame with the door partially opened to disclose the improved door clip in position upon the door and door frame.

Fig. 2 is an elevation of the door clip member carried by the door frame.

Fig. 3 is a detail sectional view on the plane of line 3—3 of Fig. 2 looking in the direction indicated by the arrows.

Fig. 4 is a detail elevation of the door clip member carried by the door frame.

Fig. 5 is an elevation of the door clip member carried by the door.

Fig. 6 is a view similar to Fig. 5 and at 45 right angles thereto and showing the clip in its locked position in the clip member.

Fig. 7 is a detail elevation of the block cover of the door clip member carried by the door, this view showing the inner side of the cover.

Fig. 8 is a detail elevation of the grooved block forming a part of the door clip member carried by the door.

Fig. 9 is a detail elevation of the spring pressed plate forming a part of the door clip member carried by the door frame, this view showing the manner of attaching a spring to the spring pressed plate.

Fig. 10 is a side elevation of Fig. 6. Referring more in detail to the drawings in which similar reference characters designate corresponding parts throughout the several views, A represents the part carried by the door frame while B represents the part carried by the door.

The part A of the screen door clip includes 75 a casing 6 having offset upper and lower flanges 7 adapted to be secured to the door frame 8 by suitable securing members 9. This may be readily understood by referring to Figs. 1, 2 and 3 of the drawings. The casing 6 has open end portions with inwardly turned flanges 10 at the upper and lower sides thereof to retain in proper position within the casing 6 the spring inclosing tray 11 having a closed back and closed 80 end portions, as shown clearly in Fig. 3. The closed end portions of the tray 11 are engaged by the flanges 10 of the casing 6, to prevent withdrawal of the tray 11. Mounted centrally on the rear wall of the tray 11, 85 as shown at 12, is a centre spring guide post 13. The spring 14 is engaged around the post 13. The spring 14 bears outwardly upon the outwardly pressed central portion 15' of the plate 15 adapted to work in the outer open side of the tray 11. The casing 6 is also provided with an outwardly pressed central portion 16 with an opening 17 formed therein through which a suitable 90 tool may be inserted to press inwardly the spring plate 15, if required. The end portions 18 are curved inwardly slightly so as to permit ready insertion of the staple 19 of the door carried part B, as will be 95 clearly understood.

By referring to Figs. 1, 2, 3, 4 and 9 the construction of the member carried by the door frame may be readily understood.

The part B includes the elongated staple 19, previously mentioned and the support 110

ing block 20 for the turned ends 21 of the staple legs. The block 20 is provided with suitable grooves 22 in its inclined outer face and the ends 21 of the staple legs are retained in proper position within the grooves 22 by the covering plate 23 for the block 20 and the securing members 24 extended through said covering plate 23 and through the block 20. The securing members 24 are also extended into the door 25, to retain the block 20 in proper position on said door 25. The covering plate 23 has suitable perforated extensions or flanges 26 through which securing members may be engaged and extended into the door 25. It is evident that the main portion of the staple 19 of the part B will be extended at substantially right angles from the door face on which the part B is mounted.

20 It is believed the complete construction and operation of the screen door clip may now be clearly understood from the foregoing paragraphs taken in connection with the accompanying drawings without further detailed description. It may be briefly stated, however, that when the parts A and B are properly mounted, respectively, on the door frame 8 and the door 25 so as to be opposite one another, the engagement of the staple 19 in the casing 6 will be assured as the door 25 closes.

As the staple 19 enters one end of the casing 6 between the outer wall thereof and the plate 15, the latter will be forced inwardly and the spring 14 compressed. By the time the door 25 is completely closed the bight portion 19' of the staple 19 will have passed between the spring pressed plate 15 and the outer side of the casing 6 so that the central bight portions 19' of the staple 19 will project through the inner end of the casing 6. The plate 15 will serve to cooperate with the outer side of the casing 6 in clamping the staple 19 and thereby retaining the door 25 in closed position until sufficient pressure is exerted against the door to open the same. As the door 25 opens, the staple 19 will be withdrawn from its position between the plate 15 and the outer side of the casing 6. The spring 14 serves to resiliently retain the plate 15 in its outermost or operative position. It is also evident that the staple 19 may be of sufficient length with respect to the other parts of the device to permit the engagement of a catch or the like on the extended bight portion 19' of the staple 19 projecting through the end of the casing 6 when the door is closed. This would then serve to lock the door in closed position and prevent unauthorized parties from opening the door from without. I show for this purpose a spring catch 27 secured to the door jamb in such a position that the bight of the staple may be engaged by the shoulder of the catch from which it

can only be disengaged by the depression of the catch. When it is required to open the door from the outside the catch is pressed back and held by a pivoted button 28.

When the door is to be taken down and stored away, the staple 19 may be readily removed from upon the block 20 and the main portion of the staple 19 inserted between the plate 15 and the outer wall of the casing 6 with the staple 19 turned so as to position the ends 21 of the staple legs against one end of the tray 11. This provides for a secure holding of the staple 19 by the door frame carried member A until again required for use. This method of storing away the staple 19 also results in the removal of objectional projections from the door while the latter is in storage or while being carried from one place to another.

It is believed the complete construction and operation of the screen door clip may now be readily understood by parties familiar with this art without further detailed description.

An important advantage of my clip is that the spring is compressed by the action of the staple which tends to its long life as it is found that, in the ordinary type of clip in which the springs are subjected to sharp elongation, particularly under certain climatic conditions, the springs are liable to snap.

While the preferred embodiment of the invention has been disclosed, it is to be understood that minor changes may be resorted to within the scope of what is claimed without departing from the spirit of the invention.

What I claim as my invention is:

1. A screen door clip comprising a receiving member adapted to be secured upon a door frame, said receiving member including a casing, a spring pressed plate cooperating with said casing and an engaging member adapted to be fixed to the door, said engaging member including a projecting staple portion for engagement between the spring pressed plate and the opposite portion of the casing.

2. A screen door clip comprising a stationary receiving member adapted to be mounted on a door frame and an engaging member adapted to be fixed to a door, said receiving member including a casing and a spring pressed plate mounted therein, said engaging member including a projecting staple portion for engagement in the casing of the receiving member, said casing and said spring pressed plate co-operating for clamping engagement with the projecting staple portion of the engaging member when said door is closed.

3. A screen door clip comprising a receiving member and an engaging member, one of said members being adapted to be mounted

on a door frame while the remaining member is carried by a door, said receiving member including a casing having open ends, a tray supported in said casing, a spring 5 pressed plate reciprocally positioned in said tray opposite one side of said casing, means within said tray for resiliently retaining the spring pressed plate in engagement with said side of said casing, said engaging member 10 including an extended portion for engagement between said spring pressed plate and said side of said casing, said spring pressed plate having turned end portions opposite the open ends of said casing to prevent 15 catching of the engaging member on said receiving member.

4. A screen door clip comprising a receiving member and an engaging member, said receiving member including a casing having 20 an outwardly pressed and perforated portion in one side, a spring pressed plate mounted in said casing opposite said side of the latter, said spring pressed plate having an outwardly pressed central portion and 25 turned end portions opposite the open ends of the casing, means supported in said casing and engaged with the outwardly pressed portion of said spring pressed plate to resiliently retain the latter in operative position, said engaging member including a projecting 30 staple for engagement through the end of said casing between said side of the casing and the said spring pressed plate.

5. A screen door clip comprising a receiving member and an engaging member adapted 35 to be mounted on a door frame and a door, said engaging member including a supporting block, a projecting staple member having turned ends mounted on said block, said 40 block having grooves for the ends of said staple member, a retaining covering plate for said supporting block, said supporting block having a beveled upper face, said covering plate serving to retain the staple member 45 on said block, said receiving member including a casing and a spring pressed plate working 50 therein for cooperation with said casing in clamping the staple member extending therebetween when said door is closed.

6. A screen door clip comprising a receiv-

ing member adapted to be secured upon a door frame, said receiving member including a casing, a spring pressed plate co-operating with said casing and an engaging member 55 adapted to be carried by the door, said engaging member including a staple mounting means and a staple carried by said means for engagement between the spring pressed plate and the opposite portion of the casing, said 60 staple being adapted to be withdrawn from said staple mounting means and inserted in reversed position between the spring pressed plate and the opposite portion of the casing when said staple is not required for use. 65

7. A screen door clip comprising a receiving member adapted to be secured upon a door frame and an engaging member adapted to be carried by the door, said engaging member including a staple mounting means and a staple carried thereby for interlocking engagement with said receiving member, said staple being adapted to be removed from the staple mounting means and engaged in the receiving member when the 75 door clip is not in use.

8. A screen door clip comprising a receiving member adapted to be secured to a door frame and provided with a friction grip; a staple adapted to be secured to the door and to project through the receiving member in engagement with the friction grip; and a spring catch adapted to be secured to the door frame to spring back and engage the bight of the staple when the door is closed. 85

9. A screen door clip comprising a receiving member adapted to be secured to a door frame and provided with a friction grip; a staple adapted to be secured to the door and to project through the receiving member in engagement with the friction grip; a spring catch adapted to be secured to the door frame to spring back and engage the bight of the staple when the door is closed; and a pivoted button adapted to be engaged with the catch to hold it in in-operative position. 90

Signed at Strathroy, Ont., this 9th day of Sept., 1922.

JOHN HEARD.
